UNITED STATES PATENT OFFICE.

CLIMIE E. HILL, OF SEATTLE, WASHINGTON.

LIQUID-FEEDING DEVICE.

Application filed October 27, 1924. Serial No. 745,964.

This invention relates to improvements in liquid feeding devices, and more particularly to means for automatically controlling the feeding of a liquid sterilizer into the mains 5 of a water supply system, it being the principal object of the invention to provide means of the above character for use in connection with pumps, especially those that are driven by electrically operated motors, 10 and which operates to deliver the sterilizing liquid into the suction pipe of the pump prior to the delivery of the water to the distributing mains.

More specifically, the invention resides in 15 the provision of automatically controlled valve mechanism whereby a sterilizing solution may be diluted to a desired degree and then fed into the suction pipe of a water supply pump.

Other objects reside in the various details of construction and combination of 20 parts embodied in the invention and in their mode of operation.

In accomplishing these and other objects, 25 I have provided the improved details of construction, the preferred forms of which are illustrated in the accompanying drawings, wherein—

Figure 1 is a view showing in section, the 30 parts of a sterilizer feeding mechanism embodying the present invention.

Figure 2 is a plan view of the solution containing tank and float mechanism.

Figure 3 is a sectional view of a device 35 of an alternative type of construction.

Figure 4 is a view showing diagrammatically the arrangement of the device and its connections with a water supply pump.

Referring more in detail to the several 40 views of the drawings—

1 designates what may be a small storage tank or receptacle into which a liquid sterilizing solution may be fed by gravity or other pressure from a source of supply, designated 45 at 1^a, through a conduit 2. The conduit communicates with the tank through an opening 3 in the base thereof at one end and the opening is tapered to provide a valve seat 4 from and against which the lower, 50 tapered end 5 of a valve stem 6 may be adjusted to control the flow of the liquid into the tank. The valve stem 6 is slidably contained in a guide frame 7 fixed within the tank and is automatically adjusted in accordance with the rise and fall of liquid by 55 means of a float 8 that is fixed at the end

of a lever 9 pivotally supported by a pin 10 within the guide frame. The shorter end of the lever has operative connection with the valve pin so that the vessel will normally 60 be kept about half full or more of liquid.

At the opposite end of the tank is an outlet 12 into which the nipple 13 of the housing 14, of a regulating valve, is threaded. The flow of liquid from the tank into the 65 valve housing 14 is under the control of a valve stem 17 having a tapered lower end 15 adapted to a seat 16 leading into the opening or outlet 12 and flow from the valve housing through a base or discharge opening 70 18 therein is under the control of a manually adjustable valve stem 19 extended upwardly and threaded through a packed gland 20 and provided at its end with a wheel 21 whereby it may be rotated to adjust the area of the discharge opening and rate of discharge.

The upper end of the valve stem 17 is connected by means of a short link 23 with the armature 24 of a solenoid 25. The solenoid coil is electrically connected by wires 80 26—26' with the circuit wires 27—27' through which electrical energy is supplied to an electric motor M that operates the pump P, so that when the motor circuit is closed, the solenoid will be energized and the armature will be lifted so as to move the valve stem 17 upwardly to open the port 12. A switch 59 is interposed in the circuit connections as shown in Figure 4, 85 and when the switch circuit is opened, the solenoid is de-energized and the valve stem is moved downwardly to close the outlet 12. The armature is supported by an arm 28 which in turn is pivotally supported from a 90 pin 29 and a spring 30 is attached to the arm to draw the armature away from the solenoid and positively close the valve when the circuit is opened.

Located below the discharge opening 18 of the regulating valve, to receive the liquid therefrom is a second tank 60 in which the sterilizing solution is diluted and which is of practically the same construction as the tank 1 and has a fresh water inlet 31 at one end under the control of a manually adjustable valve stem 32. A conduit 34 from a source of fresh water supply is connected to the opening 31 to supply water to the tank 105 in accordance with the adjustment of stem 32.

At the other end of the tank 30 is a base

outlet 35 with which a conduit 36 is attached and which leads to the suction pipe 61 of the pump; the pump having a discharge pipe 62. This outlet 35 has a tapered valve seat 37 from and against which the tapered end 38 of a valve stem 39 may be adjusted to control the flow into the conduit 36. The valve stem is slidably supported in a guide frame 40 and is under the control of a float 41 at the end of a lever 42 that has operative connection with the stem and is pivotally carried at its other end by a pivot pin 43 in the guide frame 40. This float operates to close the opening 35 as the level of liquid goes down and opens to a more or less degree in accordance with the rise of liquid in the tank.

Assuming that the parts are so constructed and arranged the use and mode of operation is as follows:

A suitable sterilizing solution is admitted from the source of supply 1^a into tank 1 through conduit 2. At a certain level of the liquid, the valve stem 6 closes the inlet opening 3. The valve stem 19 is then adjusted so that when valve 17 is opened a certain amount will be permitted to flow into the diluting tank.

When the circuit of the pumping motor is closed by switch 59, the solenoid will be energized and valve stem 17 will be lifted to open the outlet 12 so that the solution may flow into the lower tank. As the level of the solution in tank 1 goes down, the float 35 actuates valve stem 6 to open passage 5 to admit the solution from the supply as is needed to maintain a certain level in the tank.

The extent to which the sterilizing solution is diluted is controlled by the adjustment of valve stem 19 and valve stem 32 and the rate at which it is used from the tank 60 is dependent on the degree of suction pressure through conduit 36.

As the pump operates, the diluted solution is taken into a suction pipe 61 from conduit 36 and is mixed in the pump with the fresh water as the water is delivered through a discharge pipe 62 into the mains.

In Figure 3 I have illustrated an alternative construction wherein the diluting tank and its associated parts are omitted and a closed glass receptacle 50 is connected directly with the valve housing 14 and from the base of this receptacle a conduit 51 leads to the water supply.

Having thus described my invention, what I claim as new therein and desire to secure by Letters-Patent, is:

1. The combination with a source of supply of liquid sterilizing agent, a fresh water supply and a conduit through which water to be treated is delivered, of a sterilizer feeding mechanism comprising a storage tank

and a diluting tank, each having an inlet and a discharge port; the inlet port of said storage tank being connected with the source of supply of a sterilizing agent and the discharge port being located to discharge into the diluting tank; said inlet port of the diluting tank being connected with the water supply and its discharge port being connected with the said conduit; valve mechanism operable to control the flow of sterilizing agent into the storage tank and another valve mechanism for controlling flow from the diluting tank into the conduit.

2. The combination with a source of supply of liquid sterilizing agent, a fresh water supply and the suction pipe of a pump, of a sterilizer feeding mechanism comprising a storage tank and a diluting tank, each having an inlet and a discharge port; the inlet port of said storage tank being connected with the source of supply of a sterilizing agent and the discharge port being located to discharge into the diluting tank; said inlet port of the diluting tank being connected with the water supply and its discharge port being connected with the pump suction pipe, a float valve mechanism operable to automatically control the flow of sterilizing agent into the storage tank, a float valve mechanism operable to automatically control the flow from the diluting tank, a manually adjustable valve mechanism for controlling the rate of flow from the storage tank and a manually adjustable valve for controlling flow of fresh water into the diluting tank.

3. The combination with a source of supply of liquid sterilizing agent, a fresh water supply, a suction pipe of a pump and an electric circuit, of a feeding mechanism comprising a storage tank and a diluting tank each having an inlet and a discharge port, the inlet port of said storage tank being connected with the source of supply of the sterilizing agent and discharge port being located to discharge into the diluting tank; said inlet port of the diluting tank being connected with the water supply and its discharge being connected with the pump suction pipe, float valve mechanism operable to automatically control the flow of the sterilizing agent into the storage tank, solenoid connection with the circuit, a valve operable by the solenoid to control the flow from the storage tank into the diluting tank, a float valve mechanism in the diluting tank to control the flow to the suction pipe, and manually adjustable means for controlling the rate of flow of water into the diluting tank.

Signed at Seattle, King County, Washington, this 16th day of October, 1924.

CLIMIE E. HILL.
